UNITED STATES PATENT OFFICE.

STEPHEN HENRY PURDY, OF FULTONVILLE, NEW YORK.

APPARATUS FOR CASTING WIRE-NETTING TIES.

SPECIFICATION forming part of Letters Patent No. 684,525, dated October 15, 1901.

Application filed April 11, 1901. Serial No. 55,384. (No model.)

To all whom it may concern:

Be it known that I, STEPHEN HENRY PURDY, a citizen of the United States, residing at Fultonville, in the county of Montgomery and 5 State of New York, have invented certain new and useful Improvements in Apparatus for Casting Wire-Netting Ties; and I do declare the following to be a full, clear, and exact description of the invention, such as will enable others skilled in the art to which it app- 10 pertains to make and use the same.

This invention relates to apparatus for casting molten metal, and particularly to an apparatus for casting the ties used to connect the vertical and horizontal strands of 15 wire-netting together at their points of intersection; and the object of the invention is to provide an apparatus of this character whereby the operation of casting the ties of poultry- 20 coops and other like wirework may be conveniently and expeditiously performed.

With these and other objects in view, which will appear as the nature of the invention is better understood, the invention consists in 25 certain novel features of construction, combination, and arrangement of parts, as will be hereinafter more fully described, and particularly pointed out in the appended claims.

In the accompanying drawings, Figure 1 is 30 a view in elevation of one side of a casting apparatus embodying my invention, showing the sliding mold-bar retracted to separate the mold-sections. Fig. 2 is a similar view of the opposite side of the apparatus, showing 35 the mold-bar fed up to close the mold-sections. Fig. 3 is a top plan view of the apparatus with parts arranged as in Fig. 1. Fig. 4 is a vertical cross-section through the apparatus on a line between the fixed and mov- 40 able mold-sections and looking toward the supporting-standard, showing a section of a poultry-coop frame arranged in position for having the strands of the wire-netting thereof tied together. Fig. 5 is a horizontal section 45 on the line 5 5 of Fig. 1. Fig. 6 is a detail vertical longitudinal section on line 6 6 of Fig. 5. Figs. 7 and 8 are perspective views of a stationary and a fixed mold-section. Fig. 9 is a vertical section through the melting- 50 pot, taken on the line of the valves; and Fig. 10 is a horizontal section thereof, taken on the line 10 10 of Fig. 9.

Referring now more particularly to the drawings, in which like reference characters designate corresponding parts throughout the 55 several views, the numeral 1 represents a base or bed plate upon the rear portion of which is mounted a supporting-standard 2, to which are secured upper and lower forwardly-projecting guideways 3 and 4, each composed 60 of a pair of parallel bars connected at their rear ends to said standards and at their free ends to blocks or distance-pieces 5, which hold the bars properly spaced apart and have inner beveled faces 6 for a purpose hereinafter described.

Mounted to slide at its upper and lower ends in the guideways 3 and 4 toward and from the front face of the supporting-standard 2 is a vertical mold carrier-bar 7, which 70 is provided at each end with a head 8, having a beveled outer face 9. An operating rod or bar 10 reciprocates vertically in the guideways 3 and 4 in rear of the mold carrier-bar 7 and is provided at its ends with wedge-shaped heads or contact-pieces 11 11', which are adapted to traverse the beveled faces 6 and 9 of the blocks 5 and the heads 8 on said carrier-bar to force said bar toward the standard 2 when said rod or bar 10 is moved upwardly and to allow the carrier-bar to move backward or away from the standard when the operating-bar moves downwardly. Retracting-springs 12 connect the upper and lower ends of the mold carrier-bar 7 with the 75 outer ends of the guideways 3 and 4 and exert their energy to retract the carrier-bar or draw it away from the standard 2, and a spring 13 connects the operating-bar 10 with the lower guideway 4 to retract said bar or move 80 it downwardly. The wedge-shaped head 11' upon the lower end of the bar 10 is slotted or bifurcated to form two projections 14 and 15, one of which is adapted to fit within a slot 16 in the forward end of a treadle-lever 17 85 and the other to bear upon the upper surface of said lever. The said treadle-lever 17 is pivoted between lugs 18, formed upon the forward end of the base 1, and has an outwardly-extending footpiece 19, whereby it 90 may be depressed to elevate the operating-rod 10. When said rod is operated through the instrumentality of the treadle-lever in this manner, the wedge-shaped heads 11 11' 95

thereon are forced upwardly between and ride upon the beveled faces of the distance-blocks 5 and heads 8 and force the mold carrier-bar 7 toward the standard 2 in a manner 5 readily understood. When the treadle is released, the spring 13 retracts the bar 10 or draws it downwardly, leaving the carrier-bar 7 free to be retracted by the springs 12. A pivoted pawl 20 is provided upon the operating-bar 10 to engage a shoulder 21, formed upon the mold carrier-bar 7, to maintain the operating-bar in an elevated position when it is desired to hold the mold carrier-bar projected to keep the mold-sections closed, as 15 will be hereinafter more fully described.

The standard 2 and mold carrier-bar 7 are provided upon their inner or meeting faces with T-shaped grooves 22, and upon the standard are mounted one or more fixed mold-sections 23, and upon the carrier-bar a corresponding number of counterpart movable mold-sections 24. The two sets of mold-sections are adjustably mounted upon the respective bars, each mold comprising a support 25, provided with a tongue 26, which enters the groove 22 and is adjustably mounted upon its support through the medium of screw-headed bolts 27, which project into said grooves and carry nuts 28, which 30 lie in the cross portion of the T-shaped groove and bear against the outer wall thereof, and thus clamp the mold-supporting plate 25 in position. Through the medium of these bolts the mold-sections on both the supporting-standard 2 and the carrier-bar 7 may be vertically adjusted with relation to each other to increase or decrease the distance between the molds to adapt them for operating upon wire network in which the horizontal strands 35 are disposed at different distances apart. 40

In the operation of the apparatus after the molds have been in use and become heated it is frequently necessary to adjust them to a slight degree to compensate for expansion 45 and contraction and to bring the mold-chambers of the opposing sets of molds on the supporting-standard and mold carrier-bar into accurate alinement. To this end each mold-supporting plate 25 is provided with a series 50 of set-screws 29, which bear upon the face of the supporting-standard or the mold carrier-bar, as the case may be, and adapt the molds to be adjusted to take up all slack and to be adjusted to a nicety to maintain them in 55 proper operative relation. The molds 23 and 24 correspond in form and dimensions, and each consists of a block formed in its outer face with a mold cavity or chamber 30, with which communicates a gate or channel 31, 60 opening through the upper edge of the block and serving to conduct the molten metal to said chamber 30. The chamber 30 is intersected by vertical and horizontal grooves 32 and 33, which are adapted to receive the vertical and horizontal wires of the network to 65 bring them into proper position for casting the ties to unite said wires at their points of

intersection. When the mold carrier-bar 7 is fed up into the position shown in Figs. 2 and 5, the chambers 30, channels 31, and grooves 32 and 33 of each pair of fixed and movable mold-sections are brought together and form the mold-chamber in which the casting is made and passages for the inlet of the molten metal and reception of the wires which are 70 to be tied. The frame 34, in which are mounted the vertical and horizontal strands 35 and 36 of the wire meshing or network and which constitutes a portion of the frame of a poultry-coop, is supported upon rollers 37 upon the 75 vertically-slid transverse carriage 38, mounted upon the supporting-standard 2, which carriage is secured to said standard by means of a bolt 39, projecting into the groove 22 and carrying a nut 40, which occupies the 80 cross portion of said groove and holds the carriage in position. The mode of adjusting the carriage will be obvious from this construction. The wires 35 and 36, which are to be joined or tied at their points of intersection, are first mounted in a suitable frame, such as the frame 34, and the latter placed in position upon the rollers 37, upon which it may be moved transversely to bring said wires successively into operative position. 85 By reference to Fig. 2 the manner of bringing the wires into position for casting the tie will be readily understood, and it will be seen that the horizontal wire strands 36 when in operative position lie within the horizontal 90 grooves 33, while the vertical wire strands 35 lie within the vertical grooves 32, thereby bringing the contacting portions of the vertical and horizontal strands at their points of intersection in line with the mold-chambers 36, 95 ready for the casting of the tie about them which is to bind them together. To enable the wires to be readily brought into proper positions, guides 41—two in number, one for each vertical wire and one for each horizontal 100 wire—are secured upon the bottom and one side of each of the fixed mold-sections 23.

Mounted upon the supporting-standard 2 is a bracket 42, which receives the stem 43 of the melting-pot 44, which is adjustably 105 mounted in an opening therein by means of set-screws 45, whereby the melting-pot may be raised and lowered as desired. On said stem 43 is arranged a burner 46, which may be adapted for burning gas or gasolene and 110 the flames from which heat the melting-pot 44. From one side of the melting-pot 44 projects a trough or runway 47, provided with channels 48, corresponding in number to the 115 number of molds employed, which channels receive the molten metal from the pot and conduct it to the tubes or pipes 49, which 120 convey it to the molds. The molten metal feeds through each pipe or tube to the mold, to 125 which it leads by gravity, and the free end 130 of each pipe is secured by means of a suitable fastening 50 to each fixed mold-section 23 to discharge the molten metal into the corresponding channels 31, forming the gate or

runway of each mold, through which it passes to the mold-chamber 30. The metal in the mold-chamber is thereby cast about the vertical and horizontal strands of wire at their points of intersection to form the connecting-ties 54. The melting-pot 44 is provided with discharge-passages 55, which communicate with the said channels 48 in the trough 47 and are governed by valves 56, each of which is provided with a cup or pocket 57 of a size to receive the exact amount of molten metal to be supplied to each mold-chamber to form the tie. When the valves are turned to move the cups or pockets 57 away from the channels 48, said cups or pockets are brought into alignment with the passages 55 and are filled with molten metal. Upon the reverse movement of the valves the cups or pockets 57 will again be brought into alignment with the channels and the molten metal therein will run through said channels and discharge into the pipes 49, which will convey it to the molds. The valves are adapted to be operated simultaneously through the medium of operating-levers 58, which are connected at their outer ends to a handle 59 for operating them in unison. When the handle 59 is drawn outwardly or in a direction away from the supporting-standard 2, the valves are moved to bring the cups or pockets 57 into alignment with the channels 48, and a reverse movement of said handle brings said cups or pockets into alignment with the discharge-passages 55.

In operation the frame 34 is mounted upon the rollers 37 of the carriage 38 and moved transversely or laterally of the supporting-standard 2 to bring the vertical and horizontal strands of the wires 35 and 36 at their points of intersection into the guides 41, which hold them in proper alignment to be forced into the grooves 32 and 33. The treadle-lever 17 is then depressed to force the operating-bar 10 upwardly, whereby the mold carrier-bar 7 is moved toward the supporting-standard 2 and each pair of fixed and movable mold-sections 23 and 24 are closed together, as shown in Figs. 2 and 5. The handle 59 of the levers 58 is then drawn outwardly or away from the standard 2 to bring the cups or pockets 57 of the valves 56 into alignment with the discharge-passages 55. Said cups or pockets then become filled with molten metal, and the handle 59 is moved inwardly or toward the standard 2 to reverse the motion of the valves and bring said pockets into alignment with the channels 48. The molten metal then discharges into said channel 48 and runs therefrom into the pipes 49, and thence discharges into the gates or channels 31 of the molds, which conducts the metal into the mold-chamber 30, in which it is allowed to solidify and form the tie 54. The treadle-lever 17 is then released, whereupon the movable carrier-bar 7 is retracted and the frame 34 is moved transversely on the rollers 37 to bring the wires in position for the formation

of ties at other points of intersection. Should it be desired to hold the mold-sections closed while the operation of casting is being performed, this may be accomplished when the operating-bar 10 is moved upwardly by simply engaging the pawl 20 with the shoulder 21. Upon releasing this pawl the springs 12 and 13 will retract the operating-bar and moveable carrier-bar in the manner heretofore described.

From the foregoing description, taken in connection with the accompanying drawings, the construction, mode of operation, and advantages of the invention will be readily understood without a further extended description. Changes in the form, proportion, and minor details of construction may be made within the scope of the invention without departing from the spirit or sacrificing any of the advantages thereof.

Having thus fully described my invention, what I claim as new, and desire to secure by Letters Patent, is—

1. In a casting apparatus of the character described, the combination of a stationary vertical standard, upper and lower horizontal guides supported by the standard, a vertical mold carrier-bar slidable in said guides toward and from the standard, vertically and inwardly and outwardly adjustable mold-sections upon the standard and carrier-bar, a melting-pot mounted upon the standard, means for controlling the flow of metal therefrom to the molds, and means for sliding the mold carrier-bar toward and from the standard, substantially as described.

2. In a casting apparatus of the character described, the combination of a vertical supporting-standard, a vertical mold carrier-bar mounted to move toward and from said standard, mold-sections vertically adjustable upon the standard and carrier-bar and adapted to be moved into and out of engagement by the movement of said bar, a vertically-adjustable support between the standard and bar for the frame carrying the wires to be tied, a melting-pot, means for conveying the molten metal from the melting-pot to the molds, valves controlling the flow of molten metal, and means for operating the movable mold carrier-bar, substantially as described.

3. In a casting apparatus of the character described, the combination of a vertical supporting-standard, upper and lower horizontal guides, a mold carrier-bar movable in said guides toward and from said standard, adjustable mold-sections upon the meeting faces of the standard and mold carrier-bar, a vertically-moving operating rod or bar having engaging portions adapted to engage the mold carrier-bar to move the same toward the standard, springs for retracting the mold carrier-bar, and means for moving the said operating-bar, substantially as described.

4. In a casting apparatus of the character described, the combination of a supporting-standard carrying adjustable mold-sections,

upper and lower guideways supported by said standard, a mold carrier-bar provided with inclined projections and mounted in said guides and movable toward and from the standard 5 and carrying adjustable mold-sections coöperating with those on the standard, a supporting-carriage upon the supporting-standard and adjustable thereon, an operating-bar movable in the guides and provided with 10 wedge-shaped heads adapted to engage the inclined projections on the carrier-bar to move the same toward the supporting-standard, springs for retracting the operating-bar, springs for retracting the movable carrier-bar, a lever for operating said operating-bar, and means for holding the operating-bar elevated to maintain the mold carrier-bar in its 15 forwardly-adjusted position with the mold-sections engaging with each other, substantially as described.

5. In a casting apparatus of the character described, the combination of a supporting-standard carrying mold-sections, upper and lower guideways supported by said standard 25 and provided at their rear ends with inclined faces, a mold carrier-bar mounted in said guides and movable toward and from the standard and carrying mold-sections coöperating with those on the standard, said bar being 30 provided at its upper and lower ends with rear inclined faces, a supporting-carriage upon the supporting-standard, an operating-bar vertically movable in the guides and provided with wedge-shaped heads adapted to engage 35 the said inclined faces upon the guides and

carrier-bar to move the latter toward the supporting-standard, the lower wedge-shaped head being slotted or bifurcated to form two projections, an operating-lever having a slot adapted to receive one of said projections and 40 upon which lever the other projection bears, springs for retracting the operating-bar, springs for retracting the movable carrier-bar, and means for holding the operating-bar elevated to maintain the mold carrier-bar in 45 its forwardly-adjusted position with the mold-sections in contact, substantially as described.

6. In a casting apparatus of the character described, the combination of a supporting-standard carrying mold-sections, upper and lower guideways supported by said standard, a mold carrier-bar mounted in said guides 50 movable toward and from the standard and carrying mold-sections coöperating with those on the standard, a supporting-carriage upon 55 the supporting-standard, an operating-bar vertically movable in the guides and provided with wedge-shaped heads adapted to engage the carrier-bar to move the same toward the supporting-standard, springs for retracting 60 the operating-bar, springs for retracting the movable carrier-bar, and a lever for operating said operating-bar, substantially as described.

In testimony whereof I have hereunto set my hand in presence of two subscribing witnesses.

STEPHEN HENRY PURDY.
